PLATE HOLDER

Margaret E. Michalek, 430 Monte Vista Road,
Arcadia, Calif. 91006

Filed Apr. 14, 1969, Ser. No. 16,710

Term of patent 14 years

Int. Cl. D7—01

U.S. Cl. D44—10

FIG. 1 is a top plan view of a plate holder showing my new design;

FIG. 2 is an edge elevational view;

FIG. 3 is a transverse sectional view; and

FIG. 4 is a reduced scale bottom plan view.

I claim:

The ornamental design for a plate holder, as shown.
